REFRIGERATED STORAGE CONTAINER FOR
TRANSPORTING FROZEN PRODUCTS

Russell Stover, Kansas City, Mo.

Application August 13, 1938, Serial No. 224,831

2 Claims. (Cl. 62—91.5)

This invention relates to containers and more particularly to refrigerated storage and shipping containers for normally liquid material frozen to a substantially solid state.

5 It contemplates more especially the provision of an improved, simple, and comparatively inexpensive container or plurality of containers that are normally collapsible and non-rigid to confine normally materials frozen to a substantially solid 10 state.

Numerous types of cartons and containers have heretofore been proposed for the storage and shipment of normally unstable commodities such as ice cream and the like. Known types of containers are comparatively expensive and certain of these are incapable of re-use so as to constitute a comparatively heavy expense item in the storage and shipment of normally liquid materials frozen to a substantially solid state.

20 One object of the present invention is to provide an improved container for the storage and shipment of normally unstable commodities.

Another object is to provide non-rigid containers that are capable of receiving storage and shipping cartons of normally unstable commodities in conjunction with a refrigerant such as dry ice.

Still another object is to provide a plurality of non-rigid inexpensive containers that are processed to provide an insulated member to confine a refrigerant and a shipping container for normally unstable contents.

A further object is to provide a plurality of nested non-rigid containers having suitable insulating qualities for confining a refrigerant and a storage container for normally liquid material frozen to a substantially solid state.

40 A still further object is to provide a plurality of non-rigid containers in conjunction with spacers and a refrigerant to confine and afford the shipment of normally liquid materials frozen to a substantially solid state without any change in the consistency thereof.

Still a further object is to provide a plurality of 45 collapsible non-rigid paper containers that may be fitted with a refrigerant and spacers for the confinement of a storage container for normally liquid material frozen to a substantially solid state.

50 Other objects and advantages will appear from the following description of an illustrative embodiment of the present invention.

In the drawing:

Figure 1 is a sectional view in elevation of a 55 plurality of nested containers defining a refrig-

erant with a storage container for unstable commodities in accordance with the teachings of the present invention.

Figure 2 is a fragmentary sectional view in elevation of a series of nested containers similar to that shown in Figure 1 in conjunction with spacers to define an outline thereof.

Figure 3 is a plan view of the container shown in Figure 1, parts thereof being broken away to clarify the showing.

Figure 4 is a plan view of a perforated disc of a spacer of the type shown in conjunction with the nested containers illustrated in Figure 2.

Figure 5 is a plan view of a collapsed container of the type utilized in connection with the arrangements shown in Figures 1 to 3 inclusive.

The structure selected for illustration comprises a plurality of collapsible non-rigid containers 10, 11, 12, 13, and 14, in this instance five, which are of slightly increased size relative to each other 20 to afford their nested relationship with a slight air space 15, 16, 17 and 18 therebetween. The containers 10 to 14 inclusive are preferably of the self-closing collapsible type (Figure 5), each having a bottom 19 and upstanding walls 20 which are creased and folded longitudinally along and intermediate the side walls to permit the self-closing collapsing thereof with the bottom 19 disposed adjacent thereto in overlapping relation therewith.

30 The wall 20 of each of the containers 10 to 14 inclusive is provided with an overlapping portion 21 having an adhesive to effect a joinder therebetween in the customary manner. The containers 10 to 14 inclusive are preferably though not essentially prepared from non-rigid paper of sufficient thickness to possess thermal insulating qualities that may be collapsed together in assembled relation or separately depending upon the dictates of commercial practice. The interior 40 of the external container 10 is sized to permit the reception of a substance confining medium such as a rigid container 22 which is filled with normally liquid material frozen to a substantially solid state and has a detachable closure 23 associated therewith.

45 The external dimensions of the rigid storage container 22 are sufficiently less than the non-rigid container 10 to provide an annular space 24 therebetween so that the refrigerant is accessible to 50 the exterior of the storage container 22. It will be observed that the containers 10 to 14 inclusive have the wall 20 thereof of sufficient length to be disposed upon the rigid container 22 with its rigid closure 23 so as to provide an end enclosure 55

region 25 that may be gathered or otherwise folded to provide a seal for the interiors thereof, the thermal seal being effected by any suitable fastening expedient such as a cord or tying member 26 that tightly embraces the end of the gathered enclosing portion 25.

In one embodiment (Figure 1), the nested containers 10 to 14 inclusive are opened and then maintained in a substantially preformed rigid 10 shape by means of a solid refrigerant such as slabs of solidified carbon dioxide commonly known as dry ice 27 and 28 disposed at the bottom and top of the rigid container 22 with its closure 23 so as to provide an annular space 24 therearound 15 so that the refrigerant gas such as carbon dioxide will fill the annular space 24 around the rigid container 22 to maintain the contents in a substantially solid state.

It is preferable though not essential to 20 impregnate or coat the inside non-rigid container 10 and the external non-rigid container 14 with tar or other suitable insulating material so as to further reduce any possible thermal transmission through the minute wells inherent in the material 25 from which the collapsible containers 10 to 14 are prepared. Then, too, the nested containers 10 to 14 are preferably though not essentially enclosed in a burlap exterior enclosure 29 which is beyond the containers 10 to 14 and tied together by a 30 fastener 26 so as to provide better wearing qualities to the nested containers 10 to 14 while in transit and to render more durable the handling thereof.

In the modified embodiment shown in Figure 2, 35 the structure described in connection with the first embodiment (Figure 1), is substantially similar and alike in every detail except for the provision of spacer discs 30 and 31 that may be prepared or otherwise formed of corrugated paper to 40 correspond with the cross section of the inside container 10 in order to hold such in open or expanded position against closing. In order to permit the refrigerant gas to pass around and into the annular space 24, the corrugated spacer discs 45 30 and 31 are perforated as at 32 (Figure 4) to provide communication on both sides thereof. To this end, a refrigerant such as dry ice slabs 27' and 28' are somewhat smaller than the interior cross section of the inside container 10 in the 50 event spacer discs 30-31 are utilized to hold the nested non-rigid containers 10 to 14 in expanded position against collapsing; however, the carbon dioxide gas emitted by the dry ice slabs 27'-28' also serves to expand and maintain the containers 10 to 14 rigid.

It will be observed that the apertures 32 in the spacer discs 30-31 are disposed concentrically in uniform spaced relation to correspond with the diameter of the annular chamber 24 to afford 60 direct communication of the refrigerant gas thereto for passage therein. It should be observed that as the refrigerant such as dry ice slabs 27-28 or 27'-28' is gradually converted into its gaseous state, such will further expand 65 the nested containers 10-14 inclusive and any excess gases will bleed through the gathered en-

closure ends 25 that are held together and fastened by means of the tying member 26; however, the tying member 26 will permit bleeding under pressure so as to preclude rupture to the containers 10 to 14 inclusive.

With the arrangement of parts described above, it will be apparent that a very simple and comparatively inexpensive refrigerated shipping container or containers have been provided that are durable and dependable to maintain the contents 10 of the rigid container 22 in its substantially frozen initial state. Then, too, all excess weight of the component elements has been eliminated and this is conducive to minimum transportation charges. With the collapsible feature of the 15 containers 10 to 14 inclusive as well as the external burlap container 29 in the event the latter is employed as an optional expedient, it will require little space to maintain an inventory of 20 these nested containers with their auxiliary parts, this being a decided advantage in commercial practice for storage and shipping expedients of 25 this character.

Various changes may be made in the embodiment of the invention herein specifically described without departing from the invention or sacrificing any advantages or features thereof, and nothing herein shall be construed as a limitation upon the invention, its concept or structural embodiment as to the whole or any part 30 thereof except as defined in the appended claims.

I claim:

1. In a storage and shipping container for normally liquid material frozen to a substantially solid state, the combination with a plurality of 35 non-rigid nested containers that are not self-sustaining nor form-retaining, said containers being open at one end thereof, of solid refrigerants disposed in vertically spaced relation in said containers proximate to the closed bottom and open 40 top thereof, the outer and inner walls of said nested non-rigid containers being coated with a thermal insulating material, a rigid container for confining normally liquid material frozen to a substantially solid state, said rigid container being disposed in said non-rigid containers proximate and between said refrigerants, and means 45 for closing the end of said non-rigid containers.

2. In a storage and shipping container for normally liquid material frozen to a substantially 50 solid state, the combination with a plurality of non-rigid nested containers that are not self-sustaining nor form-retaining, said containers being open at one end thereof, of solid refrigerants disposed in vertically spaced relation in said containers proximate to the closed bottom and open 55 top thereof, the outer and inner walls of said nested non-rigid containers being coated with a thermal insulating material, a rigid container for confining normally liquid material frozen to a 60 substantially solid state, said rigid container being disposed in said non-rigid containers proximate and between said refrigerants, and means for closing the end of said non-rigid containers.
